SKI BOOT

Claude A. Van Horn, Lambertville, N. J.

Application March 16, 1954, Serial No. 29,563

Term of patent 14 years

(Cl. D7—7)

Fig. 1

Fig. 3

Fig. 1 is a front perspective view of a ski boot showing my new design, illustrating the boot in an open position; Fig. 2 is a side perspective view thereof in a closed position; and

Fig. 3 is a rear perspective view of the ski boot.

I claim:

The ornamental design for a ski boot, as shown.
